[57] ABSTRACT

A carburetor having an induction passage with a variably positionable throttle valve situated therein has an idle fuel discharge port situated downstream of the throttle valve, when the throttle valve is in its curb idle position, and a transfer port or slot for discharging fuel into the induction passage as the throttle valve is moved from its curb idle position toward a more fully opened position; the transfer port or slot is formed of a generally hollow body-like member inserted in the structure defining the carburetor so as to have a slot which is formed in the body-like member in communication with the induction passage and the interior space of the hollow body-like member; a plug is inserted within the interior space of the body-like member and the slot and located as to thereby define a terminal portion of the slot in a location precisely as required with respect to the throttle valve when the throttle valve is in its curb idle position.

CARBURETOR FUEL TRANSFER DISCHARGE PORT

BACKGROUND OF THE INVENTION

As is well known in the art, carburetors employ, among other systems, an idle fuel system and a main fuel system. The main fuel system usually comprises a main fuel discharge nozzle (cooperating with related metering restriction means) situated generally within the throat of a venturi section of the induction passage and is therefore responsive to and effective for discharging fuel in accordance with the venturi vacuum generated by the flow of air therethrough. However, generally, at low engine speeds, including idle engine operation, the velocity of air flow through the venturi is insufficient to create a suitable metering vacuum.

Therefore, the idle fuel delivery system, which comprises an idle fuel discharge port communicating with the induction passage downstream of the throttle valve when in its idle position, is employed to provide the required fuel during the lower range of engine operation. The idle fuel system, by virtue of the location of the idle fuel discharge port, is exposed and responsive to the value of the engine intake manifold vacuum generated downstream of the throttle. It should also be remembered that, with certain possible exceptions, the value of the manifold vacuum will be the greatest at idle and will diminish as the throttle is progressively moved in an opening direction. Therefore, with merely a fixed idle fuel discharge port, the fuel-air mixture would become leaner in fuel as the throttle were moved in the opening direction because of the fixed discharge area of the idle fuel discharge port and the reduction in the value of manifold vacuum.

Consequently, in order to provide a smooth transition from the idle fuel system (responsive to engine vacuum) to the main fuel system (responsive to venturi vacuum created after air flow has attained a predetermined velocity) the prior art has provided a fuel transfer port or slot communicating with the induction passage and supplied with fuel generally from the idle fuel system. Although the exact position of the lower or terminal end of the transfer slot or port is often dependent on the particular characteristics of the engine which is to employ the carburetor, generally, the transfer slot is so located within the induction passage as to be traversed by an edge of the throttle valve as the throttle valve is being moved toward a more fully opened position. In so traversing the transfer port, the manifold vacuum existing immediately below the throttle valve is permitted to act on the progressively increasing exposed area of the transfer slot thereby increasing fuel flow therethrough and into the induction passage.

Although in years past the transfer slots or ports of the prior art have proven to be generally satisfactory, they are now found to be unsatisfactory especially in view of the automotive industry's concern with reducing the level of engine exhaust emissions.

That is, in accordance with the accepted practice, such transfer slots or ports were cut into the body forming the carburetor by a machining process which, as is of course obvious, requires certain dimensional tolerances. Other manufacturing tolerances are, of course, required as for example with respect to the location of the throttle shaft, the size of the throttle shaft at the point where it supports the throttle valve, the size and

configuration of the throttle valve, and the size of the induction passage itself. All of such tolerances often result in having the terminal end of the transfer slot located not exactly where it should be with respect to the edge of the throttle valve when the throttle valve is in its idle position. Depending on where such terminal end actually occurs will also often determine whether the carburetor will have an overly rich fuel-air mixture or even "dead-spots" during the time that the throttle valve starts traversing the transfer port.

Accordingly, the invention as herein disclosed is primarily concerned with the solution of the above as well as other related problems.

SUMMARY OF THE INVENTION

According to the invention, apparatus for defining a fuel discharge port in a fuel supply device having a housing with an induction passage formed therethrough and a variably positionable throttle valve situated within said induction passage, comprises a body adapted to be inserted into a receiving opening formed in said housing, a first passage formed in said body for communication with a source of fuel, a slot-like opening formed in said body so as to complete communication between said first passage and said induction passage, and an end plugging member receivable within said first passage, said plugging member being variably positionable in said first passage and effective to define an end surface of said slot-like opening, said plugging member being selectively positioned as to define said end surface at a selected position with respect to an edge of said throttle valve when said throttle valve is in a nominally closed position.

DESCRIPTION OF THE DRAWINGS

In the drawings, wherein for purposes of clarity certain details and elements may be omitted from one or more views:

FIG. 1 is a top plan view of a throttle body portion of a multiinduction passage carburetor employing the invention;

FIG. 2 is an enlarged fragmentary cross-sectional view taken generally on the plane of line 2-2 of FIG. 1 and looking in the direction of the arrows;

FIG. 3 is an enlarged fragmentary cross-sectional view taken generally on the plane of line 3-3 of FIG. 1 and looking in the direction of the arrows;

FIG. 4 is an enlarged fragmentary cross-sectional view taken generally on the plane of line 4-4 of FIG. 1 and looking in the direction of the arrows;

FIG. 5 is a somewhat enlarged exploded perspective view of certain of the elements shown in FIG. 3;

FIGS. 6 and 7 are views somewhat similar to that of FIG. 5 but illustrating other embodiments; and

FIG. 8 is a fragmentary perspective view of a modified form of one of the elements comprising the invention.

DESCRIPTION OF THE PREFERRED EMBODIMENTS

Referring now in greater detail to the drawings, FIG. 1, by way of example, illustrates a throttle body 10 having primary bores or induction passage portions 12 and 14 and secondary bores or induction passage portions 16 and 18. A primary throttle shaft 19 journaled within the throttle body 10, and extending transversely through the induction passages 12 and 14, has secured

thereto primary throttle valves 20 and 22 respectively located within bores 12 and 14. Similarly, a secondary throttle shaft 24 journaled within the throttle body 10, and extending transversely through the induction passages 16 and 18, has secured thereto secondary throttle valves 26 and 28 respectively located within bores 16 and 18. Throttle shafts 19 and 24 may be provided with suitable control linkage means respectively fragmentarily illustrated at 30 and 32.

Groove-like channels 34 and 36 may be formed in the upper surface of throttle body 10 so as to receive therein fuel from the related idle fuel system and, in turn, distribute such fuel to conduit portions leading to idle fuel discharge ports. For example, channel 34 communicates at its opposite ends with downwardly extending conduit portions 38 and 40 respectively communicating and feeding idle fuel discharge ports 42 and 44 while channel 36 communicates at its opposite ends with similar downwardly extending conduit portions 46 and 48 communicating and feeding similarly situated idle fuel discharge ports 50 and 52.

As generally typically illustrated in FIG. 2, a main carburetor body 54 (fragmentarily illustrated) may be carried atop the throttle body 10 in a manner containing a suitable seal or gasket 56 therebetween with the gasket, among other things, serving to close off the upper portion of the channels 34 and 36 except, of course, at the point where they are fed by the idle fuel system. Similarly, a gasket or seal 58 may be provided and contained between the lower surface of throttle body 10 and the upper surface of the engine intake manifold 60 to which the throttle body 10 is secured.

Considering FIGS. 1, 3 and 5, it can be seen that the transfer port means 62 is comprised of a hollow-like insert body 64 and a cooperating plug 66 which are received within a slot or recess 68 formed in the throttle body 10. As best seen in FIG. 5, insert body 64 may be comprised as to have parallel external side walls 70, 72, end wall portions 74, 76 parallel to end wall 75 and top and bottom walls 78 and 80 through which a passageway 82 extends.

Body 64 is also provided with a rib-like extension 84 which has an outwardly directed surface 86 preferably of an arcuate configuration conforming to the radius of the induction bore 12. A slot 88 is formed through the rib 84 so as to communicate with the main internal passage 82.

As generally illustrated in FIGS. 1 and 3, recess or receiving groove 68 may be formed through throttle body 10 and have a cross-sectional configuration closely approximating the cross-sectional configuration of the insert body 64.

The plug 66, shown in each of FIGS. 1, 3 and 5, may be comprised of a main body portion having an outer contoured surface 90 closely conforming to the cross-sectional configuration of passage 82 of insert body 64. A rib-like protrusion or extension 92, carried by the body of plug 66, has an outer surface 94 which is preferably contoured to form a continuation of the contour of surfaces 86. The ends of plug 66 are determined by end surfaces 96 and 98. As generally illustrated by FIGS. 1 and 3, plug 66 is received within passageway 82 of insert body 64 in a manner causing the rib portion 92 to be closely received within slot 88 of body 64.

As best shown in FIG. 3, insert body 64, which may be formed of a suitable plastic, is preferably positioned

so as to have its upper most surface 78 abutting against the lower surface of gasket 56 and to thereby have the upper portion of its inner passage 82 in communication with suitable conduit means 100 leading to a source of fuel (not shown but well known in the art). The body 64 may be suitably fixed in place within the groove or recess 68, in the position shown, as by employing, for example, a suitable adhesive for cementing body 64 to receiving recess 68.

The plug 66 is generally slideably received within passageway 82, and slot 88, and moved axially therewith until the top surface 96 thereof is positioned in a desired relationship with respect to the edge of the throttle valve 20 when the throttle valve is in its idle position. For purposes of illustration, and not by way of limitation, this has been shown as having top surface 96 of plug 66 at a level half way between the upper and lower surfaces of the edge of the throttle valve 20.

Plug 66 may also be made of plastic and, after adjustment, fixed in place within body 64 by, for example, employing a suitable adhesive for cementing the plug 66 to the insert body 64.

As a consequence, fuel passage means are defined by conduit means 100, internal passage 82 down to a terminal end surface 96 and out through the open (unblocked) upper portion of slot 88, above surface 96, and into the induction passage 12. Of course, such fuel flow will occur only as the throttle valve 20 is rotated so as to have edge 21 thereof traverse the open portion of slot 88 and, in such case, only through so much of that portion of the slot 88 as is exposed to the vacuum existing posterior to the throttle valve 20.

In view of the above, it should be apparent that the invention enables the construction and positioning of a transfer port or slot (defined by the open portion of slot 88 above the level of surface 96 of plug 66 and rib 92) to exactly the desired position relative to the edge of the related throttle valve regardless of the manufacturing tolerances.

FIGS. 6 and 7 illustrate what may be considered as second embodiments of the elements shown in FIG. 5. Elements of FIGS. 6 and 7 which are like or similar to those of FIG. 5, or FIG. 3, or identified with like reference numbers with a suffix *a*.

In comparing insert body 64a to body 64 it can be seen that the only real difference therebetween is the elimination of rib portion 84 in body 64a and the enlargement of surfaces 86a which are totally exposed to the interior of the induction passage 18 as to form a wall portion thereof.

In comparing plug 66a to plug 66 it can be seen that plug 66a, in addition to the rib 92a, has a further extension 102 with an abutment surface 104 formed thereon which, as indicated, may be generally stepped with respect to top surface 96a.

The insert body 64a and plug 66a may be inserted within the receiving recess 68a in the manner generally described with reference to body 64 and plug 66 in FIG. 3. However, as will be noticed in FIG. 4, the abutment surface 104 enables the quick and accurate positioning of the plug 66a merely by abuttingly engaging the lower surface of edge 21a, of throttle valve 28, against abutment surface 104 and rotating the throttle valve 28 to its idle position where, automatically, the proper position and relative location of upper surface 96a of plug 66a is achieved.

Although the insert body and cooperating plug of the invention may be formed from any suitable material, it is nevertheless contemplated that acetal resin, a high melting, highly crystalline, thermoplastic polymer having a chemical structure represented by the formula $(-\text{OCH}_2-)_n$ would be highly suited for their formation. In this connection, an acetal resin derived by polymerization of formaldehyde and sold commercially under the trademark, Delrin, would be particularly suited. Delrin acetal resin has been tested by the ASTM (American Society of Testing Materials) and the results of such tests are available in ASTM report Nos. D-638, D-790, D-792 and D-696.

Further, if the components are to be cemented in place, various adhesives could be employed among which could be a suitable epoxy.

Various modifications of the invention are, of course, possible. For example, the insert body, as 64, could be of a length equal to the length of the cooperating receiving recess 68 so as to be axially contained between the gaskets 56 and 58.

Further, the insert body need not have a continuous slot, as at 88, formed therethrough. It is contemplated that in addition to possibly providing a contoured shape to the slot 88, the slot may be further modified by extending for only a portion of the length of body 64 with the upper most portion of rib 84 being solid across the top resulting in a modified slot 88b as fragmentarily shown at FIG. 8. Such contouring of the slot may be desirable in certain instances in order to achieve a totally smooth transition from the idle system to the main fuel system.

Although only selected preferred embodiments and modifications of the invention have been disclosed and described, it is apparent that other embodiments and modifications of the invention are possible within the scope of the appended claims.

I claim:

1. Apparatus for defining a fuel discharge port in a fuel supply device having a housing with an induction passage formed therethrough and a variably positionable throttle valve situated within said induction passage, comprising a body adapted to be inserted into a receiving opening formed in said housing, a first passage formed in said body for communication with a source of fuel, a slot-like opening formed in said body so as to complete communication between said first

passage and said induction passage, and an end plugging member receivable within said first passage, said plugging member being variably positionable in said first passage and effective to define an end surface of said slot-like opening, said plugging member being selectively positioned as to define said end surface at a selected position with respect to an edge of said throttle valve when said throttle valve is in a nominally closed position.

10 2. Apparatus according to claim 1, wherein said plugging member includes a portion extending into said slot-like opening a distance sufficient to have a terminal surface thereof substantially coextensive with the surface of said induction passage.

15 3. Apparatus according to claim 1, wherein said plugging member includes a portion extending through said slot-like opening and projecting into said induction passage, said portion including a reference abutment surface adapted to be operatively engaged by said edge of said throttle valve whereby movement of said throttle valve to said nominally closed position simultaneously causes corresponding movement of said plugging member to said selected position.

20 4. Apparatus according to claim 3, wherein said abutment surface is formed in a stepped relationship to said end surface in said slot-like opening whereby said end surface may assume a juxtaposed position with respect to said edge of said throttle valve when said throttle valve operatively engages said abutment surface.

25 5. Apparatus according to claim 1, wherein said body is formed of Delrin, and wherein said plugging member is formed of Delrin.

30 6. Apparatus according to claim 1, wherein said plugging member is cemented within said first passage so as to maintain its selected position within said body.

35 7. Apparatus according to claim 1, wherein said slot-like opening extends for the entire length of said body.

40 8. Apparatus according to claim 1, wherein said slot-like opening extends for the entire length of said first passage.

45 9. Apparatus according to claim 1, wherein said slot-like opening is closed at one end, and wherein said one end is contoured as to present a projected area of ever diminishing size as it more nearly approaches said one end.
